UNITED STATES PATENT OFFICE.

THOMAS E. BROOKS, OF CASSOPOLIS, MICHIGAN.

SILO.

1,122,250.

Specification of Letters Patent. Patented Dec. 29, 1914.

Application filed January 19, 1914. Serial No. 812,887.

To all whom it may concern:

Be it known that I, THOMAS E. BROOKS, a citizen of the United States, residing at Cassopolis, in the county of Cass and State 5 of Michigan, have invented certain new and useful Improvements in Silos, of which the following is a specification.

The invention relates generally to an improvement in silos, and particularly to a 10 silo built up of independent sections or staves, preferably of concrete or the like, and peculiarly constructed to provide for interfitting.

The main object of the invention is the 15 construction of a silo in which the staves for the greater portion of the wall are constructed to provide complementary ribs and recesses for the interfitting connection of such staves, the similar sections adjacent 20 and forming the door openings in the silo being formed for interfitting with the main staves, and also formed on their proximate edges to receive and support sill blocks, and to receive and support the doors.

25 A still further object is to form the staves so as to interfit with each other for a portion of their length only, and to be spaced from each other for the greater portion of their length.

30 The invention in the preferred details of construction, will be described in the following specification, reference being had particularly to the accompanying drawings, in which:—

35 Figure 1 is a view in elevation of a silo constructed in accordance with my invention. Fig. 2 is a perspective view of one of the main staves. Fig. 3 is a perspective view of one of the door opening staves. Fig. 4 is 40 a similar view of the opposing door opening staves. Fig. 5 is a perspective view of one of the sill blocks. Fig. 6 is a broken perspective, viewed from the inner side, a portion of the wall of the improved silo.

45 Referring particularly to the accompanying drawings the improved silo is preferably circular in shape, and aside from the top, doors, and tie-bands, is constructed wholly of slabs or staves, of concrete or similar 50 material.

The slabs or staves making up the silo are of four distinct types, the main staves, constituting those making up the greater portion of the wall, the door opening staves, 55 of different types on opposite sides of the

door opening, and the sill blocks for supporting the doors. All the different types of staves and blocks are peculiarly constructed for interfitting, and are of appropriate curvature transversely to properly interfit to 60 complete the outline shape of the silo.

The main staves 1, shown in Fig. 2, are concrete blocks of appropriate length and thickness formed on one edge with a longitudinally extending recess 2, and on the opposite edge at the ends thereof with short longitudinally extending complementary projections or ribs 3, which extend beyond a similarly formed rib 3' intermediate said short ribs.

The door opening staves, illustrated respectively in Figs. 3 and 4, comprise block like slabs 5 and 6, similar in general size and shape to the main staves 1. The stave 5 is formed on its relatively outer longitudinal edge with ribs 7, corresponding to the ribs 3 of the main stave, and on its relatively inner longitudinal edge with a channel 9 terminating short of the respective ends of the stave. The channel 9 has 75 its respective walls 10 and 11 at right angles to each other, and in parallelism with the side edge and inner surface of the stave respectively, said channel being located at the juncture of the side edge and inner surface 80 of the stave. That edge of the stave formed with a channel 9 is also formed above the upper end of the channel with a groove 12, corresponding in size and shape to the groove 2 of the main stave, and below the 85 lower end of the channel 9 with another groove 13 alined with and corresponding to the groove 12. The remaining door stave 90 6 is formed in its relatively outer longitudinal edge with a channel 14 corresponding to the channel 2 of the main stave, and is cut away on its relatively inner longitudinal edge to present a block like projection corresponding in length to that of the channel 9 of the stave 5. The block like 95 projection coincides with the outer face of the stave, and is of less width than the stave, presenting edge shoulder 16 adjacent the inner face of the stave, as shown in Fig.

4. The relatively inner edge of the block 100 6 is formed above and below the projection 15 with centrally arranged alined ribs 17 and 18.

The sill blocks which are approximately 110 of the same width of the staves but of mate-

rially less height, are appropriately shaped slabs 19 formed on their opposing edges with grooves 20 and ribs 21, as clearly shown in Fig. 5.

- 5 The main staves are built up in silo form and relation in an obvious manner, the ribs 3 of one fitting into the grooves or recesses 2 of the other. The door opening slabs are similarly connected to the adjacent main 10 slabs, being arranged in spaced relation to form door openings. The upper and lower ends of the door opening slabs of each horizontal section of the silo, are connected by the sill blocks, the grooves 20 of which 15 operate with the ribs 17 and 18 of the immediately adjacent endwise meeting similar door opening slabs 6, the ribs 21 of the sill blocks coöperating with the recesses 12 and 13 of the endwise meeting adjacent similar 20 door opening slabs 5, all as clearly shown in Fig. 6. The door opening slabs of the respective superimposed section of the silo are thus interlocked. As thus connected the channels 9 of the door opening slabs 5 and 25 the shoulders of the door opening slabs 6, between the respective sill blocks provide bearing portions for doors 22, which doors are preferably constructed of cross strips secured by longitudinal cleats 23. The 30 channels 9 and shoulders 16 are preferably of such depth that the inner surface of the doors are flush with the inner surface of the staves. Metallic bands 24 encircle the meeting ends of the staves, being tightened 35 to secure them in practically rigid relation. The meeting ends of the main staves are preferably arranged in offset relation transversely of the silo, so that each stave interlocks with two adjacent staves at the meeting 40 ends to secure a more rigid structure. With the staves assembled in silo forming relation it will be noted that the ribs 3 of the main staves engage the grooves only of adjacent staves for a portion of their 45 length, and that the ribs 3' on the narrower portion of the staves does not come in contact with the adjacent staves, thus spacing the greater portion of the longitudinal edges 4 of adjacent staves from each 50 other. The reinforcing bands 24 cover the meeting edges of the staves, and as the staves are not subjected to any strain or unequal stress on those portions not covered by the bands due to their spaced relation, 55 the difficulty heretofore met with in building silos of concrete slabs due to the breaking of the slabs or staves at points not protected by the bands in the act of tightening the bands is overcome in a most effective 60 manner. After the bands are properly tightened, the spaces or openings between the staves are filled with a sealing medium, as concrete, thus insuring an absolute tight connection therebetween.
- 65 The silo may be constructed of as many

sections as desired and is provided with the usual roof 25, which may be of wood or of any desired material.

Having thus described my invention what I claim is:—

1. A silo constructed of composite staves, one of said staves being formed on its meeting edges with a channel of uniform depth, the meeting edge of the adjacent stave being formed with a rib to fit in said channel, 75 an intermediate portion of the stave edge carrying said rib being cut away for its full width including the rib whereby to provide a rib having end portions of full dimension and an intermediate portion of 80 less dimension.

2. A composite stave for silos formed on one edge with a channel of uniform depth, the opposing edge of the stave having its intermediate portion cut-away throughout 85 its full width to form a recess in said edge, the portions of said edge of the stave above and below the recess being formed with ribs corresponding in size to that of the channel and each wall of the recess being formed 90 with a rib in alinement with the first mentioned ribs but of less sectional dimension than the latter.

3. A silo constructed of composite staves, the door opening edge of one of said staves being formed with a channel adjacent each 95 end thereof and an angular recess in the juncture of said edge with the face of the stave, said recess extending throughout the length of the stave between the adjacent 100 ends of the channels, the door opening edge of the opposing stave being formed adjacent each end with ribs corresponding in size and shape to said channels, and intermediate said ribs with a projection of less 105 width than the edge of the full length between adjacent ends of the ribs.

4. A silo constructed of composite staves, the door opening edge of one of said staves being formed with a channel adjacent each 110 end thereof and an angular recess in the juncture of said edge with the face of the stave, said recess extending throughout the length of the stave between the adjacent 115 ends of the channels, the door opening edge of the opposing stave being formed adjacent each end with ribs corresponding in size and shape to said channels, and intermediate said ribs with a projection of less 120 width than the edge of the full length between adjacent ends of the ribs, said projection having one edge flush with one face of the stave to present an angular recess adjacent the opposing face of the stave.

5. A silo constructed of composite staves, the door opening edge of one of said staves being formed with a channel adjacent each 125 end thereof and an angular recess in the juncture of said edge with the face of the stave, said recess extending throughout the 130

length of the stave between the adjacent ends of the channels, the door opening edge of the opposing stave being formed adjacent each end with ribs corresponding in size and shape to said channels, and intermediate said ribs with a projection of less width than the edge of the full length between adjacent ends of the ribs, said projection having one edge flush with one face of the 10 stave to present an angular recess adjacent the opposing face of the stave, and sill blocks formed on opposing edges with ribs and projections to coöperate with the chan-

nels and ribs of the door opening edges of said staves, the vertical extent of the sill 15 blocks being greater than the similar dimension of the stave channels and ribs to permit said blocks to coöperate with the channels and ribs of vertically-adjacent staves for interlocking said staves.

In testimony whereof I affix my signature in presence of two witnesses.

THOMAS E. BROOKS.
